UNITED STATES PATENT OFFICE.

DAVID F. STAUFFER, OF YORK, PENNSYLVANIA.

DESIGN FOR A BRETZEL OR CRACKER.

SPECIFICATION forming part of Design No. 20,860, dated June 23, 1891.

Application filed May 20, 1891. Serial No. 393,498. Term of patent 14 years.

To all whom it may concern:

Be it known that I, DAVID F. STAUFFER, a citizen of the United States, residing at York, in the county of York, State of Pennsylvania, 5 have invented and produced a new and original Design for Bretzels or Crackers, of which the following is a specification, reference being had to the accompanying drawings, forming part hereof, and in which—

10 Figure 1 is a top plan view of a bretzel, showing my design. Fig. 2 is a perspective of the design.

The leading feature of my design consists in a series of raised oval surfaces meeting at 15 a common center and presenting at their outer edges curved lines which extend inwardly and meet between each oval surface, as illustrated in the drawings.

The letter A designates the raised oval surfaces having a common center B, and C designates the curved lines at the edges, and which 20 meet at D between the raised oval surfaces.

The foregoing constitute essential features of the design. In addition to such features there is shown a scalloped or indented edge 25 formed by a series of inwardly - extending short lines E, forming an irregular outline, as illustrated. The effect of the whole is a neat and attractive design presenting a combination of curved lines most pleasing to the eye 30 and distinguished in the particulars specified from other designs heretofore employed in the same class of goods.

Having set forth the essentials of the invention, what I claim is— 35

The design for bretzels and crackers, as herein described and shown.

In testimony whereof I affix my signature in presence of two witnesses.

DAVID F. STAUFFER.
